GUIDE FOR A DRAWER

Edward L. Kaplan, Northbrook, and Gerhard Cless,
Skokie, Ill., assignors to Kenneth H. Gutner

Filed Aug. 23, 1974, Ser. No. 500,145

Term of patent 14 years

Int. Cl. D6—06

U.S. Cl. D6—191

FIG. 1 is a top plan view of the inventive drawer guide;

FIG. 2 is an enlarged and elevational view such as would be seen along the side line 2—2 of FIG. 1; and

FIG. 3 is a perspective view of the inventive drawer guide.

We claim:

The ornamental design for a guide for a drawer, as shown and described.
